US0D1105195S

(12) **United States Design Patent** (10) Patent No.: **US D1,105,195 S**
(45) Date of Patent: ** Dec. 9, 2025

(54) **BIPED ROBOT**

(71) Applicant: **UBTECH ROBOTICS CORP LTD.**,
Shenzhen (CN)

(72) Inventors: **Hang Liu**, Shenzhen (CN); **Chunjiang Fu**, Shenzhen (CN); **Yanan Hu**, Shenzhen (CN)

(73) Assignee: **UBTECH ROBOTICS CORP LTD.**,
Shenzhen (CN)

(**) Term: **15 Years**

(21) Appl. No.: **29/955,860**

(22) Filed: **Aug. 5, 2024**

(51) LOC (15) Cl. **15-99**

(52) U.S. Cl.

USPC **D15/199**

(58) **Field of Classification Search**

USPC D15/199; D21/578-583, 585, 593, 594

(57) **CLAIM**

The ornamental design for a biped robot, as shown and described.

DESCRIPTION

FIG. 1 is a front perspective view of a biped robot showing the claimed design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures show portions of the biped robot that form no part of the claimed design.

1 Claim, 8 Drawing Sheets
